UNITED STATES PATENT OFFICE.

WILLIAM C. VON WACHHOLTZ, OF HASBROUCK HEIGHTS, NEW JERSEY.

AUTOMATIC VENDING-MACHINE.

1,174,782.

Specification of Letters Patent.

Patented Mar. 7, 1916.

Application filed November 30, 1912. Serial No. 734,307.

To all whom it may concern:

Be it known that I, WILLIAM C. VON WACHHOLTZ, of Hasbrouck Heights, in the county of Bergen and State of New Jersey, have invented certain new and useful Improvements in Automatic Vending-Machines, of which the following is a specification.

My invention consists in improvements relating to that class of machines known as "Automatic vending machines" and in which certain articles, small boxes or the like, are automatically delivered one by one on depositing of a coin of certain denomination in the slot of the machine.

The object of my invention is to provide a simple and reliable machine which works entirely automatic, by the gravity of the coin and the article to be vended.

The invention consists of certain new features in the construction of the coin selector, the delivery mechanism and the combination of the various parts which will be described and claimed below.

References are to be had to the accompanying drawings forming part of this specification wherein like figures indicate the same part throughout the several views.

Figure I is an isometric outside view of the machine. Fig. II is a sectional plan of the machine on the line A—A of Fig. III. Fig. III is a sectional rear elevation of the machine on the line B—B of Figs. II and IV. Fig. IV is a sectional side elevation of the machine on the line C—C of Fig. III. Fig. V is a vertical section through the trip mechanism for washers on the line D—D of Fig. II showing a washer in tripped position. Fig. VI is the same section as Fig. V but a coin taking the place of a washer. Fig. VII is an isometric detail of the coin guide and coin selector. Fig. VIII is a section through the funnel of the coin chute showing how a coin is balanced in this funnel if the pin 39 is omitted. Fig. IX is a vertical section through the box guide 47 on the line C—C of Fig. III showing a released box falling.

The machine is used to sell cylindrical, disk shaped objects, boxes or the like which are capable of rolling on an incline. Its mechanism is contained in a casing 1, which may be of any suitable construction, but preferably of the box like shape shown in Fig. I. The front side of casing 1 has an opening 4 near the top, which is closed from

within the casing by the slot plate 5, with slot 6 for the insertion of the coin.

Below opening 4 in the center of the front side, is the main opening to the casing. It is ordinarily closed by a hingeless door 2 which is held in place by the lugs 2^a and locked by lock 3 at its top, as shown in Figs. III and IV. When door 2 is removed, access can be had to the interior of the casing for refilling the magazine and unlocking the cash drawer.

At the bottom of the front side I have arranged opening 8 which gives access to the delivery compartment 14, in which the vended article appears after a coin has been inserted in slot 6. The interior of the casing is divided in two compartments: the delivery compartment 14, which is always open to the public and the private compartment 10 which is always secluded from the public and contains the mechanism. Compartment 14 is formed by the walls 11 and 12 and roof 9, it has the opening 15 in the rear wall 11, for the removal of the cash drawer 16, opening 14^a for the vended articles in side wall 12 and opening 14^b in roof 9 for the returned coins.

The private compartment 10 comprises the balance of the interior of the casing 1, it has two extensions 13 and 13^a which reach to the bottom of casing 1 and are separated by the cross wall 11. Into space 13 I have placed the cash drawer 16 which is locked by the cupboard catch 17, the latter is fastened to wall 11 above opening 15: the bolt of this catch engages the catch plate 18 which is attached to the cash drawer 16. One end of a cord 19 is tied to knob 20 of the cupboard catch and the other end by means of screw eye 21 to the roof of the casing 1.

To the rear side of coin plate 5, (see Figs. II, III, IV.) I have attached the coin guide 22 which consists of a U shaped plate with two flanges 22^a and surrounds the coin slot 6 to prevent the meddling with the mechanism by pieces of wire, hair pins or the like. The lower opening of this coin guide leads to the coin selector 23. All these parts are preferably made of sheet metal and shown in Fig. VII. The bottom of coin selector 23 forms an inclined plane, on which the coins roll and the two sides 23^a and 23^b are inclined to the vertical line, thus forming a V shaped trough, flattened at its base. Near the entrance of the coin selector I have at-

tached the wedge shaped tongue 24 to side 23^b, at such a distance above the bottom of 23, that every coin which drops into the selector from coin guide 22, is deflected toward side 23^a and rolls along, leaning against that side. Opening 25 in the side 23^a is made of such dimensions that a coin of smaller diameter than a correct coin, drops through. Side 23^a is also provided 10 with a wedge-shaped projection or tongue 26, this tongue is placed in such position that a coin of correct size can pass underneath it, while a coin of larger size 7^b is deflected by it toward side 23^b. The latter 15 side has an opening 27 located opposite tongue 26 through which this deflected coin drops out of the coin selector; between the lower end of side 23^a and the guide piece 29 on that side, is an opening 28, and the 20 bottom of coin-selector 23 gradually widens out at this place. On the two guide pieces 29 slides shutter plate 30, which opens or closes aperture 29^a between these guide pieces. To receive coins which drop through 25 the openings 25, 27, and 29^a I have placed coin hopper 32 below the coin selector as shown in Figs. II, III, IV, V, and VI. This hopper is preferably made of sheet metal and of the form shown in the drawings, it 30 terminates at its lower end into coin return spout 33 which guides the coins into the delivery compartment 14 through opening 14^b. Near the side 23^a of the coin selector opposite opening 28 I have placed the funnel shaped inlet 34 of coin chute 35. A space 35 slightly smaller than the diameter of a correct coin is left between coin selector 23 and funnel 34; into this space protrudes the upper end of a vertical rod 36, the lower end 40 of this rod is fastened in suitable manner to coin hopper 32. A coin 7 which drops out of opening 28 takes the position shown in Fig. VI, it glides over the top of rod 36 into funnel 34, but a washer 37 is tripped 45 by rod 36 at its hole and glides down on this rod as shown in Fig. V. Coins which drop into funnel 34 occasionally take the position shown in Fig. VIII. To prevent this, I have placed pin 39 into funnel 34, 50 which prevents said position of coin 7 and insures a clear path for the same.

Coin chute 35 is preferably made of sheet metal and fastened to the side wall of the machine by suitable lugs 40. The straight 55 part of the coin chute 35 is closed on four sides and slightly inclined to the vertical line, in such a manner, that coin 7^a (see Fig. III) does not fall down, but rolls down on the inclined side of the chute, in order to 60 insure a more uniform striking of the coin against the release lever 49. The lower part of the coin chute is formed into a curve 35^a to give the coin a turn of 90° and make it roll in horizontal direction on the lowest 65 part of the chute, to the outlet at 35^b. The

curved and horizontal parts of the chute are preferably closed on three sides, but open at the top. A coin which has rolled out of the coin chute at 35^b, strikes release lever 49, operates this lever by its momentum, falls 70 on the inclined coin tray 60 and rolls down on this tray into cash drawer 16.

U shaped gutters 41 form the magazine for the boxes 42 or similar articles to be vended; these gutters are preferably made 75 of sheet metal and arranged in zig zag form as shown in Fig. III, but if space or arrangement requires it, they may be made in form of a continuous helix or in any other suitable manner. The gutters are fastened 80 by means of lugs 43 to the standards 46 which rest on the roof 9 of the delivery compartment 14. The bottom end of each upper gutter at 41^a is provided with an aperture in its bottom, to let the boxes pass 85 through and is connected to the top end of the next lower gutter at 41^b by means of a flat strip 44. The bottom part of each lower gutter is bent upward and forms a curved guide 45 which reaches above the 90 boxes 42 of the upper gutter, the upper ends of these guides are fastened to the strips 44. The upper and lower curves of these guides 45 are circular, but they are connected by a short vertical tangent, 45^a which 95 prevents the boxes from locking each other. Below the lowest or delivery end of the gutters at 38, I have placed the vertical box guide 47 which is formed by four plates. Plate 47^a forms the extreme end 100 of the lowermost gutter and is fastened to the two side walls of this gutter; the upper part of this plate is curved and extends upward above the box 42^a, to form an entering guide for the boxes. Plate 47^b forms 105 the side of the box guide opposite to 47^a, it extends lower down than that side and its lower part 47^c is bent toward 47^a to form a baffle plate on which the boxes drop. This plate prevents meddling with the box guide 110 and box retainer by means of wire, which is sometimes inserted into these parts through opening 8, the delivery compartment 14 and the delivery chute. Plate 47^c is located toward the front side of the machine and nearer to it, than the wall of the 115 lowest gutter on that side; this plate reaches down to the bottom of the casing and is fastened by flanging it at a right angle, to wall 12 by means of screws or 120 in any other suitable manner. Plate 47^d is located opposite to 47^c, its upper edge is attached to the wall of the lowest gutter on that side, it is provided with a slot 48 through which the box retainer 50 slides 125 as shown in Figs. II, IV and IX. It is also provided with an outward projection 48^a on which the box retainer rests. Box retainer 50 is a part of the release lever 49, which has the form of a bell-crank with 130

arms 49 and 49^a, this lever has three downward projections, 49^b to receive the strike of the coin, 50^a and 50^b to limit the movement of the box retainer 50. Release lever 49 is pivoted on pin 51 and supported by wall 11. One end of a tension spring 52 is attached to lever 49 and its other end to a pin 53 of standard 46. Box retainer 50 protrudes into box guide 47 through 10 aperture 48 and supports the lowest box 42^a when spring 52 exerts its tension on lever 49. The release lever 49 is placed in such position to the coin chute 35, that a coin discharged from its lowest end 35^b, 15 strikes the projection 49^b by its momentum, and causes the withdrawal of box retainer 50 from box guide 47 and thereby permits the lowest box 42^a to drop on baffle plate 47^c and from this plate to roll down on the 20 inclined delivery plate 54 into the delivery compartment 14 through opening 14^a. To return the coin when the magazine is empty I have provided the following mechanism: A flat arm 55 is fastened to a shaft 56 as 25 shown in Figs. II, III, and IV. One end of this shaft turns in journals provided in the magazine standards 46, the other end in a bearing 57 which is fastened to the rear wall of the casing. At the proper 30 place on shaft 56 a lever 58 is mounted. The free end of this lever is formed into a hook or ring, to which one end of a cord 51 is tied. This cord runs through a screw eye or other suitable means, to shutter plate 30. As long as the magazine is filled arm 35 55 rides on box 42^c as shown in Fig. III, lever 58 is in raised position and by means of cord 51 the shutter plate 30 is lowered as shown in Figs. IV and VII. When the 40 magazine is so far emptied that only two boxes 42^a and 42^b remain in the magazine, arm 55 and lever 58 drop to the positions indicated by the dotted lines in Fig. III and shutter plate 30 is raised to the position 45 shown in dotted lines in Fig. VII. The flat strips 44 which connect the gutters 41 of the magazine are fastened to the outside of the side walls of the upper gutters and to the inside of the side walls of the 50 lower gutters, this is done to prevent the boxes from falling on to the side walls of the lower gutters.

The operation of my automatic vending machine is as follows: The gutters 41 of the 55 magazine are filled, for example with boxes of cylindrical shape, by placing them in rolling position on the uppermost gutter; they roll down in these gutters and fill them; the lowest box 42^a rests on box retainer 50, its upper rim has not yet left edge 38 of the lowest gutter, as shown in Figs. IV and IX. The third box 42^c keeps arm 55 in raised position and by means of lever 58 and cord 51 the shutter plate 30 closes 60 the opening 29^a of coin selector 23 as shown

in Figs. III and VII. A coin 7 of correct size deposited through slot 6 is guided by coin guide 22 into coin selector 23, it is deflected toward side 23^a by tongue 24 and continues to roll along that side in inclined 70 position, it passes opening 25 and beneath tongue 26; by the time it reaches opening 28, it has acquired sufficient momentum to pass by this opening, but following its inclined position it swerves in outward direction and rolls on the widened part of the selector bottom until it strikes the shutter plate 30 where it rebounds, falls over on its side and drops out of opening 28. The coin then slides over the top end of rod 36 into 80 the funnel 34, it is placed in correct position by pin 39 and rolls down through coin chute 35, it assumes a horizontal direction by means of the curved chute 35^a and coming out of the chute at 35^b strikes projection 85 49^b of release lever 49 with considerable impact. By the force of this impact the tension of spring 52 is overcome and the box retainer 50 is momentarily withdrawn from the vertical box guide 47. The lowest box 90 42^a, assisted by the weight of the boxes above it, falls into the delivery chute 54, rolls down on the inclined bottom of the latter, into delivery compartment 14, where it can be reached by the customer through 95 opening 8. At the moment when the box retainer is withdrawn from box guide 47, the box 42^a enters the widened part of the box guide between the plates 47^c and 47^d and is pushed by the returning release lever toward side 47^c, it permits thereby the release lever to return to its original position before the next following box 42^b reaches the box retainer 50. If a coin 7 is inserted into slot 6 when the machine is empty and shutter plate 30 is in raised position as previously described, then the coin will also pass along the side 23^a of the coin selector, but as it is not stopped by shutter plate 30 it will pass out under this plate through opening 100 29^a, and fall into hopper 32 as shown by 7^d Fig. IV and coins larger than the desired coin, deflected by tongue 26 fall through opening 27 into hopper 32 as shown by 7^b in Fig. IV, all these coins are returned by 110 spout 33 into delivery compartment 14. A coin which is lighter in weight than the correct coin is not able to strike release lever 49 with sufficient momentum and therefore no article is vended by it. To empty the 115 cash drawer 16 of its contents, lock 3 is opened and door 2 lifted out, a pull on cord 19 opens the catch 17 and releases the cash drawer, which can then be pulled out into delivery compartment 14 by means of a 120 wire hook (not shown) which is inserted into a hole 61 provided for this purpose in the front side of the cash drawer. The drawer can then be emptied of its contents by reaching through delivery opening 8. 130

Having thus described my invention, what I claim as new and desire to secure by Letters Patent is:

1. In a magazine for vending machines, composed of separate sections of U shaped gutters, forming a single track, and placed one above the other, in alternately inclined position, means to prevent the locking of the vended articles at the gap between an upper and a lower gutter, consisting of a guard, curved in its upper and lower portions and flat in its middle section, said guard being attached to the upper end of the lever gutter, and extending above the articles in the upper gutter, guide strips attached to the inside of the vertical legs of the lower gutter and passing the outside of the upper gutter to guide the inner edges of the vended article.
2. In an automatic vending machine a series of gutters, of U shaped cross section held one above the other, in alternately inclined position, by a single set of uprights near the middle of their incline, leaving open spaces between the vertical legs of a gutter and those of the next one above, adjustable means on said uprights to swivel said gutters into the desired inclination.
3. In an automatic vending machine for rolling objects, a magazine, a stationary vertical guide-chute attached to the lowest end of said magazine, said guide-chute, being wider transversely than the transverse width of the magazine, to permit a transverse movement of the object within said chute, a bell crank, movable perpendicularly against the flat side of the object, extending into said guide-chute, to intercept one of said objects while permitting a second one to pass the front of said lever.
4. In an automatic vending machine, the combination of a magazine consisting of alternately inclined gutters, of U shaped cross section, supports attached to said gutters near their middle guide strips connecting each upper gutter to the next lower one, a stationary guide-chute of greater transverse width than the gutters, attached to the lowest of said gutters, a horizontally movable lever, entering said chute to intercept

an object falling therein, an inclined baffle plate attached to the guide-chute, below said lever and a delivery board, having a differently directed inclination than the baffle plate, below said guide-chute.

5. In an automatic vending machine, a magazine, a stationary vertical guide-chute, attached to said magazine, a horizontally movable bell crank, in its normal position partly closing the passage of said guide-chute and supporting the lowest object to be vended, said bell crank adapted to be withdrawn from said guide-chute and means to restore said bell crank into its normal position.

6. In a vending machine for rolling objects, a magazine, a guide-chute to receive the objects from the magazine, rigidly attached thereto, bell crank means attached to the guide-chute to support the lowest object within the chute when in normal position, and to release it by a horizontal movement of said bell crank, and means to shift the object in axial direction within the guide-chute, while in motion.

7. In an automatic vending machine for rolling objects, a magazine, a stationary guide-chute attached thereto, said chute being wider transversely in its lower, than in its upper part, sliding means entering said chute at its wider part in horizontal direction, and axially to the objects contained therein, said sliding means being in such position, that they support the lowest object to be vended, partly in the narrow, and partly in the widened part of the guide-chute.

8. In a vending machine for rolling objects, a magazine, a stationary guide-chute attached thereto at its delivery end, a horizontally movable slide entering said guide-chute, from one of its sides, a transverse widening in said guide-chute, opposite the end of said slide, to permit an object contained therein to move laterally under pressure of said slide.
